UNITED STATES PATENT OFFICE.

HENRY S. HOPKINS, OF BROOKLYN, NEW YORK.

DRYING APPARATUS.

1,037,254.

Specification of Letters Patent.

Patented Sept. 3, 1912.

Application filed December 16, 1911. Serial No. 666,126.

To all whom it may concern:

Be it known that I, HENRY S. HOPKINS, a citizen of the United States, residing at Brooklyn, in the county of Kings, State of New York, have invented certain new and useful Improvements in Drying Apparatus, of which the following is a specification.

This invention relates to apparatus for drying in a continuous sheet or web, material, such as paper or cloth which has been subjected to some surface finishing or preparatory operation, such as coloring, top sizing, gumming, printing, etc.

One object of this invention is to provide an apparatus of the character above described, in which the material as it is fed through the drier is caused to lie snugly upon the conveyer, and prevented from curling along the edges while it dries.

Another object of this invention is to provide a drier of the character described, in which a maximum length of material may be held inside the drier at any given time.

Further objects will appear from the detailed description, and will be particularly pointed out in the claims.

In the accompanying drawing which illustrates this invention; Figure 1 is an elevation of one embodiment of my invention; Fig. 2 is a section taken along line 2—2 of Fig. 1, looking in the direction of the arrows; Fig. 3 is a section on an enlarged scale, taken along line 3—3 of Fig. 2; Fig. 4 is a fragmental detail illustrating the disposition of the links, screen, and material; Fig. 5 is an elevation partly in section, and Fig. 6 is a plan of another embodiment of my invention. Fig. 7 is an elevation, and Fig. 8 is a plan partly in section of still another embodiment of my invention. Fig. 9 illustrates a modification.

Referring to Figs. 1 to 4, the numeral 1 indicates generally a coating machine from which the coated material 2 is fed through the drier. The latter consists of the casing 3 divided into a plurality of compartments 4, 5, and 6. I have shown only three of these compartments by way of illustration, but it may be understood that any desired number of compartments may be used. In the first and last of these compartments are mounted drums 9 and 10 actuating an endless conveyer 11, which carries the paper, fabric or other material through the drier. A blast of hot dry air is supplied to the

drier by a flue 12 communicating with compartment 6, which is farthest from the point of entrance of the material into the drier. This blast after passing over the material in compartment 6 is exhausted by a fan 13, through flue 14, into chamber 5, where it passes over the material in that compartment. The air is then exhausted by fan 15, through flue 16, into compartment 4, and so on. It will be clear that as the air passes through the successive compartments it gathers up moisture from the material, and will be more or less saturated when it is finally exhausted into the atmosphere. Should it be desired to introduce a dry blast into any of the intermediate compartments, I provide flues 17 and 18, leading from flue 12, and connecting respectively with flues 14 and 16. Any desired form of damper or control may be used in connection with flues 17 and 18 to regulate the supply of dry air.

The apparatus described so far is substantially the same as disclosed in my co-pending application S. N. 643,469.

I will now proceed to describe the improvements to which the present application is more particularly directed.

Mounted upon the endless conveyer 11 is a screen 19. This screen instead of lying flat upon the conveyer is disposed thereon, in a wavy outline as clearly shown in Fig. 3. By reason of its own weight, and also on account of the air blast, the paper will follow the curvature of the screen as it passes through the drier. This curving of the paper will prevent its curling along the edges, as will be readily understood by those skilled in the art. The screen may be held in such corrugated or wavy outline by means of sticks or rods 20, disposed in links 21 of the endless conveyer. For the reception of those rods 20, the links may be formed with raised middle portions 22 and curved or sloping edges 23. These curved edges 23 may also be made use of in actuating swinging gates 24. These gates are pivoted in the walls separating the compartments and serve to prevent the communication of the air between the compartments while the troughs of the waves pass the openings between the compartments. Rollers 25 are provided on pintles at the lower corners of each gate and co-operating with the curved surface of the links. It may be understood

that any other desired means may be used for keeping closed the opening between the compartments.

In the embodiment of my invention illustrated in Figs. 5 and 6, I show my improved form of screen used in connection with a blast of air which may be directed substantially in the direction of the length of the paper or other material to be dried, and the 10 exhaust flues disposed on the same side of the material as the flues conveying the blast. In these Figs. 5 and 6, 30 indicates a flue conveying the hot dry air and having outlet branches 31, 32, 33, 34, etc. Exhaust flue 15 35 may be connected to an exhaust fan or any other means for exhausting the air, and may be provided with branches 36, 37, 38, 39, etc. These exhaust flues extend into the casing above the paper and serve to exhaust the air which has become saturated 20 with moisture after passing over the surface of the material. Both the inlet and exhaust flues may be formed with diverging mouths 40 and 41, so as to extend across the 25 entire width of the paper.

In the embodiment of my invention illustrated in Figs. 7 and 8, I show a form in which my improved screen is used in connection with a drier in which the blast of 30 air is conveyed through nozzles, directing the blast with a certain amount of velocity and impact against the material. 50 indicates a flue conveying the hot dry blast, and 51 indicates the nozzles extending from 35 flue 50 into the interior of the casing. These nozzles may be formed with diverging mouths 52, so as to extend across the entire width of the material. 53 indicates an exhaust flue having branches 54 extending 40 into the casing at any desired point and serving to carry away the air after it has become saturated with the moisture from the material.

Fig. 9 illustrates a modification of the 45 contour of screen 19, in which the wavy outline is sharper and steeper than in the other modifications of my invention. Such outline or contour serves to further increase the length of material which may be held at 50 one time in any given length of the drier.

It will be clear that, by my construction of screen, I prevent the curling of the edges of the material which is being dried, and thus eliminate a great source of waste which 55 has hitherto existed when paper or like material is being dried. It will also be clear that by my construction the curling of material is avoided independently of any blast pressure or any suction used to keep the material down snugly upon the conveyer. By 60 reason also of the wavy outline of the conveyer, I am able to keep a greater length of material within a given length of drier, and, therefore, increase the length of time in 65 which the material as a whole is kept within

the drier. In this way I can reduce the length of the drier without sacrificing any of its drying efficiency.

I have illustrated various specific embodiments of my invention but do not wish, 70 however, to be limited thereby, for various embodiments of this invention may be made without departing from the spirit and scope of the invention as defined in the claims.

I claim:

1. In drying apparatus, a casing, a conveyer passing through the casing and adapted to convey the material to be dried, and a screen mounted upon the conveyer, said screen having a wavy or corrugated 80 outline in the direction of its length.

2. In apparatus for drying sheets and fabrics, a conveyer adapted to carry the material to be dried, said conveyer having a wavy outline in the direction of its length 85 and adapted to cause the material to lie thereon in a series of waves, while said material is being dried.

3. In drying apparatus for drying sheets and fabrics, a conveyer adapted to carry 90 the material to be dried, said conveyer having a wavy outline in the direction of its length, and adapted to cause the material to lie thereon in a series of waves, and means for causing a blast of air to pass over 95 the surface of the material to dry the same.

4. In drying apparatus, a casing divided into a plurality of compartments, a conveyer passing through the compartments and adapted to carry the material to be dried, and means for adjusting to the contour of the conveyer the openings in the walls of the compartments as the conveyer 100 passes through them.

5. In drying apparatus, a casing divided 105 into a plurality of compartments, a conveyer passing through the compartments and adapted to carry the material to be dried, and hinged gates provided for the walls of the compartments through which 110 the conveyer passes, and adapted to automatically adjust to the contour of the conveyer the opening formed in said walls.

6. In drying apparatus, a casing divided 115 into a plurality of compartments, a conveyer passing through the compartments, and adapted to carry the material to be dried the walls separating the compartments being provided with slots, said conveyer having a wavy outline in the direction of its length, 120 adjustable means for adjusting to the contour of the conveyer the slots in the walls between the compartments, and means for automatically operating said adjustable means.

7. In drying apparatus, a casing divided 125 into a plurality of compartments, a conveyer passing through the compartments and adapted to carry the material to be dried, the walls separating the compart- 130

- ments being provided with slots, said conveyer having a wavy outline in the direction of its length, adjustable means for adjusting to the contour of the conveyer the 5 slots in the walls between the compartments, means movable with the conveyer for automatically operating said adjustable means.
8. In drying apparatus, a casing divided into a plurality of compartments, a conveyer passing through the compartments and adapted to carry the material to be dried, the walls separating the compartments being provided with slots, said conveyer having a wavy outline in the direction of its length swinging gates adapted to adjust to the contour of the conveyer the 10 slots in said walls, and a series of cams carried by conveyer and adapted to operate said swinging gates.
- 15 9. In a drying apparatus, an endless conveyer comprising a linked chain, the links of the chain having raised portions, rods passing through said raised portions,
- adjacent to their upper edge, and a screen 25 passing over the rods and bent into the form of a wavy outline in the direction of its length.
10. In a drying apparatus, a casing divided into a plurality of compartments, a conveyer passing through the compartments 30 and adapted to carry the material to be dried, the walls separating the compartments being provided with slots, said conveyer comprising a linked chain, the links of the chain having raised portions, a screen 35 on the conveyer and fashioned into a wavy outline in the direction of its length, gates on the walls separating the compartments and adapted to adjust the slots to the contour of the conveyer, said raised portions 40 of the links serving to automatically operate said gates.
